UNITED STATES PATENT OFFICE.

OTTO BALOGH, OF CHICAGO, ILLINOIS.

DESIGN FOR A SHIRT-WAIST BOX.

No. 38,302.

Specification for Design.

Patented Oct. 30, 1906.

Application filed May 14, 1906. Serial No. 316,863. Term of patent 3½ years.

To all whom it may concern:

Be it known that I, OTTO BALOGH, a citizen of the United States, residing at Chicago, in the county of Cook and State of Illinois, have invented a new, original, and ornamental Design for a Shirt-Waist Box.

The accompanying drawing illustrates a design in accordance with my invention.

I claim—

The ornamental design for a shirt-waist box, as shown.

OTTO BALOGH.
